WESTERN ELECTRIC COMPANY, INCORPORATED, OF NEW YORK, N. Y., A CORPORA-
TION OF NEW YORK.

TELEPHONE-EXCHANGE SYSTEM.

Application filed October 16, 1923. Serial No. 668,806.

To all whom it may concern:

Be it known that we, GERALD DEAKIN and LIPA POLINKOWSKY, citizens of the United States of America and Russia, respectively, residing at Antwerp, Kingdom of Belgium, have invented certain new and useful Improvements in Telephone-Exchange Systems, of which the following is a full, clear, concise, and exact description.

10 This invention relates to a telephone exchange system and particularly to a system in which preference is given to toll calls over local calls.

15 In systems of this character, it is usual to arrange that upon a toll call being received for a subscriber who is already busy in a local connection, either as a calling or a called subscriber, the connection previously established with a local subscriber may be 20 broken down and the toll connection extended to the local subscriber's line. Difficulties are met with when applying a system of this character to a private branch exchange group of lines as it is usual to arrange that 25 the final selector switches for establishing toll connections hunt over those private branch exchange lines which are busy either in local or toll connections in an endeavor to find a line which is entirely free. In 30 doing this, the final selector switch may move over all the lines of the private exchange group and will come to rest in connection with the final line therein, but if the line is busy in a toll connection, it is not 35 disturbed. As a result, the toll connection may not be extended to the private branch exchange although a number of the lines of the group extending thereto may be occupied only in local calls.

40 It is therefore an object of this invention to provide an improved system of this character which will obviate the disadvantage referred to.

45 In the terminal bank group or groups of final selectors provided for operating to select an idle one of a group of private branch exchange lines, the lines of the group, with the exception of the last are

differentiated from the last line of the group and private or ordinary subscribers' lines, by 50 the fact that the cut-off relays and message register magnets which are connected in parallel to the sleeve terminals of the lines are not shunted by a resistance element. When, therefore, a final selector tests the 55 terminal of a trunk line in a group that is busy, if it is other than the last line, the test potential will be such as to prevent the energization of the private branch exchange relay of the selector and, consequently, the 60 selector brushes will be advanced to the terminal of the next line. If the selector is thus advanced over terminals of busy lines until its brushes rest on the terminals of the last line of the group, then due to 65 the additional shunting resistance, the busy potential encountered by the test brush of the selector will be greater and the private branch exchange test relay of the selector 70 will energize to arrest the brushes of the selector upon the terminals of the last line of the group.

The object of this invention is realized by arranging that upon a line of a private branch exchange group of lines being taken 75 into use for a toll connection, the line immediately preceding this line in the group thereupon becomes marked as a final line thereof by the connection of a resistance element in shunt of the usual cut-off relay and message register magnet. When this latter line is taken into use in a toll connection, the line immediately preceding it is caused also to test as the final line in the group. This operation may be extended over all or 80 part of the lines of the group and in this manner hunting is prevented beyond the line immediately preceding the line of the group which is the last to be engaged in a toll connection.

85 Referring to the accompanying drawings, Fig. 1 shows a final selector of the type which may be employed in a full mechanical system to extend local connections to direct 90 subscribers' lines or lines of a private branch exchange group or may be employed by the 95

toll operator to extend toll connections to such lines. The brushes of a second final selector of the same type are also indicated at 199.

5 Fig. 2 shows schematically a group of private branch exchange lines terminating in the bank of a final selector 150 through which toll connections may be extended, and also terminating in the bank of a final selector 10 for 199 through which only local connections may be extended.

It has not been considered necessary to disclose herein all of the circuits essential to the establishment of either local or toll connections, and therefore, only the final selector has been illustrated. For a full disclosure of an automatic system of the type to which this invention is applicable, reference may be had 20 to the patent to Lipa Polinkowsky No. 1,381,431, issued June 14, 1921. In the following description, it will first be assumed that the first four lines of the private branch exchange group shown in Fig. 2 are occupied 25 in local calls established over the brushes of final selectors such as 199 having access to the lower group of multiple terminals shown at the left of Fig. 2. It will be further assumed that the last line of the 30 group is idle and that a toll connection is to be established to the branch exchange over the final selector switch 150 disclosed in Fig. 1. The desired toll connection is extended to the trunk terminals of the idle 35 final selector 150 in the manner fully set forth in the aforementioned patent.

As soon as the final selector is taken for use, the fundamental circuit is closed at the sender, relay 172 is energized and sequence 40 switch 100 is advanced into position 2, over a circuit extending from the armature and front contact of relay 172, through the contact of cam 102. With sequence switch 100 in position 2, the operation of the tripping 45 spindle 173 takes place, the circuit therefore including the lower contact of cam 103 and the front contact and armature of relay 172. The interrupter 174 of such tripping spindle places the usual intermittent 50 shunt upon the portion of the fundamental circuit extending to the sender over the lower contact of cam 105. Upon the completion 55 of the operation of tripping spindle 173, to cause it to release the desired set of brushes in the subsequent operation of the brush carriage, relay 172 becomes deenergized and sequence switch 100 is moved out of its second position into its fifth position.

60 Before the sequence switch 100 reaches its fifth position, the fundamental circuit is again closed at the sender in the usual manner and relay 172 being energized over the fundamental circuit, the movement of the brush carriage will take place in the fifth position of the sequence switch due to the en-

ergization of the brush carriage magnet 177 over the contact of cam 110 and the armature and front contact of relay 172. During the operation of magnet 177, and the rotation of the brush carriage, the interrupter 178 intermittently shunts the fundamental circuit with the exception of relay 172 in the usual manner. The selected set of brushes having been tripped and brought in this manner to the terminals of the first line of the desired private branch exchange group, the numerical designation indicated by the operator upon the number keys of her sender being the designation of the first line in the group, the fundamental circuit 70 will be again opened at the sender. Relay 172 thereupon deenergizes to stop the movement of the brush carriage and to close a circuit over the upper contact of cam 104, to drive the sequence switch 100 into its 75 sixth position.

With sequence switch 100 in position 6, and the brushes of the final selector resting on the terminals 208, 209 and 210, of the first line of the desired branch exchange, a 80 circuit is established from battery, through the cut-off relay 211 and the message register magnet of this line in parallel, test terminal 210, brush 133, winding of relay 196, lower contact of cam 104 to ground at the back contact of relay 172. Since as previously assumed, this line is busy, the potential on the test terminal 210 will be such as to prevent the energization of relay 196, and consequently, relay 180 is not energized. A circuit is therefore effective for the carriage magnet 177 traceable over the lower contact of cam 119, the back contact of relay 180, to ground at the contact of cam 124, 90 and the selected brush set is advanced to the terminals of the next line in the branch exchange group. If this line is also busy, the brush carriage continues in motion.

As soon, however, as the brushes of the final selector come into contact with an idle branch exchange line, in the case assumed, the last line of the group, relay 196 will be energized due to the increased potential on the test terminal 200 resulting from the connection of resistance 204 in shunt of the cut-off relay 202 and message register magnet 203 whether such line is busy or idle. The circuit of relay 196 extends from ground at the back contact of relay 172, lower contact of cam 104, relay 196, brush 133, terminal 200, winding of relay 201, to battery, in parallel through relay 202, magnet 203 and resistance 204. Relays 202, 201 and 110 196 energize. Relay 202 cuts off the line relay 205 from the conductors of the called line in the usual manner and relay 201 at its left contact, opens the normally closed shunt around relay 206 in the sleeve conductor of the next preceding line of the group. At its right armature and front contact, re- 115 120 125 130

lay 201 also connects battery through resistance 207 to the sleeve conductor of the next preceding line of the group in parallel with the windings of the cut-off relay and message register magnet of such line. The connection of resistance 207, therefore, establishes the same test condition on the sleeve conductor of the next to the last line of the group as is normally established by the resistance 204 on the sleeve conductor of the last line, and therefore, as long as the last line is engaged in a toll connection and relay 201 remains energized, the next to the last line is made the temporary last line of the group.

At the final selector 150, upon the energization of relay 196, a circuit is established from battery over the armature and contact of relay 196, the winding of relay 180, to ground at the contact of cam 123, whereupon relay 180 energizes, opening the circuit of the carriage magnet 177 and at its front contact closing a circuit from ground at cam 124, over the upper contact of cam 111 for driving sequence switch 100 out of position 6 into position 9. While passing through position 7, since the call has been initiated at a toll operator's position, ground potential will be applied in the manner set forth in the aforesaid patent to the ring conductor of the final selector trunk and over the contact of cam 106, through the left winding of relay 172. Relay 172 thereupon energizes, closing a circuit for the right winding of relay 185 over the lower contact of cam 108. Relay 185 energizes closing a locking circuit for itself over its left winding and left armature and front contact to ground at the front contact of relay 171, which latter relay is maintained energized from the time the final selector is seized until it is finally released. The energization of relay 185 at this time differentiates the operation of the final selector as establishing a toll connection. Had the final selector been used in a local connection, relay 185 would not operate at this time.

As the sequence switch 100 passes through position 8, a test is made to determine the busy or idle condition of the selected line. This circuit is closed over the test brush 133, the right winding of relay 179 to ground at the contact of cam 121, and as the line has been assumed to be idle relay 179 operates. Relay 179 thereupon locks over its left winding through the winding of relay 180 to ground at the contact of cam 123, relay 180 energizing in this locking circuit. Upon the energization of relay 180, a circuit is established from the contact of cam 124, the armature and front contact of relay 180 and the upper contact of cam 111, for advancing sequence switch 100 out of position 9 into position 10, where it stops since cam 124 is opened and relays 171 and 185 are energized.

With sequence switch 100 in position 10, the upper contact of cam 107 and the lower contact of cam 122 are closed extending the tip and ring conductors of the incoming trunk circuit over condensers 131 and 132, to the tip and ring brushes of the final selector.

The toll operator may now proceed to call the branch exchange by depressing her ringing key, whereupon a circuit is established for relay 172 over the contact of cam 106. Relay 172 upon energizing, closes a circuit over the contact of cam 102, for advancing sequence switch 100 out of position 10 into position 16, relay 172 being maintained energized after the opening of sequence switch cam 106 by a circuit including the front contact of relay 171, the left armature and front contact of relay 185, the right winding of relay 172, the left winding of relay 183, lower contact of cam 109, and winding of relay 184 to battery. The sequence switch will stop in position 16, however, due to the opening of sequence contact 102. The branch exchange is then rung directly from the toll operator's position over the direct metallic connection extending through the upper contacts of cams 113 and 116.

Upon the termination of the conversation, the restoration of the apparatus used is controlled by the toll operator in the usual manner. When the group selector preceding the final selector 150 is restored, ground potential is removed from the sleeve terminal of the trunk extending to the final selector, and relay 171 deenergizes, opening the locking circuit of relay 185 and closing a circuit over the contact of cam 118 for advancing sequence switch 100 into position 17. If the called subscriber has not as yet restored his receiver to its switchhook, relay 172 is energized in position 17 of the sequence switch over a circuit including the lower contact of cam 112, the subscriber's line loop, the upper contact of cam 113, to ground through the lower contact of cam 107. As soon as the called subscriber restores his receiver, relay 172 deenergizes closing a circuit over the upper contact of cam 104, for advancing sequence switch 100 into position 18.

In position 18, of sequence switch 100, the brush carriage of the final selector is restored in the well understood manner and having restored drives sequence switch 100 into its first normal position. The tripping spindle 173 has already been restored, the sequence switch 103 having closed a circuit through the tripping spindle magnet in position 12.

Should a second toll connection to the branch exchange be initiated during the time that the first four trunks are busy on local calls, and the last trunk is busy on the previously described toll call, the final selector used on the second toll call will be arrested with its brushes engaging the terminals of

the next to the last line of the group, which line was as already described, made temporarily the last line of the group. With the switch brushes stopped on the terminals of 5 this line, a circuit is closed as previously described through the test relay 196 of the final selector, brush 183, test terminal 213, relay 206, thence in parallel to battery through the windings of the cut-off relay 10 214 and message register magnet 215, and resistance 207. Relay 206 upon energizing connects resistance 216 to the sleeve conductor of the next preceding line rendering it temporarily the last line in the group to the 15 next incoming call.

It will be noted in this connection that relays have been shown corresponding to relays 201 and 206 in series with the sleeve conductors of the last three lines only of 20 the group, whereby the fourth, third and second lines of the group may be successively rendered the last line upon successive toll calls to the branch exchange. It is, of course, obvious that any number of the lines 25 could be similarly equipped.

The second toll call to the branch exchange will be completed by a final selector switch similar to switch 150 in the manner above set forth up to the point where the 30 line is tested by relays 179 and 180 and since as assumed, the line is busy on a local connection, relay 179 does not energize and sequence switch 100 therefore stops in position 9. In position 9, relay 184 is intermittently operated over the upper contact of cam 109, through interrupter 127, and at its front contact intermittently closes a buzzer circuit through the winding 129 of the tone coil 137, left armature and front contact of 35 relay 184, interrupter 128, buzzer 131 to battery. Tone current then flows to the toll operator's position over the lower contact of cam 107, winding 130 of the tone coil 137 and the upper contact of cam 122.

40 The operator is thereupon apprised of the fact that the wanted line is busy on a local call. Relay 172 is energized at this time as previously described, whereby sequence switch 100 is advanced out of position 9 into 45 position 10, in which position a connection is extended from the operator's position over the upper contact of cam 107 and the lower contact of cam 122 through condensers 131 and 132, to the called line. The toll operator 50 may now converse with the subscriber and inform him that as his line is desired in connection with a toll call, she is going to break down the established local connection for the purpose of the toll connection. As the manner in which this is done is not an essential 55 part of the present invention, it will not be described herein, reference being had for a full description thereof to the patent hereinbefore referred to. If the private branch 60 exchange lines are engaged in local calls

only, they will be tested and taken for use over the lower group of bank terminals illustrated in Fig. 2 and will function in the usual manner, the last line only of the group functioning as a last line.

70 The invention claimed is:

1. In a telephone exchange system, a group of lines extending to a private branch exchange, switching apparatus for extending local and toll connections to said branch 75 exchange over said lines, and means operative upon the extension of a toll connection to a line which tests as the final line of the group for causing the line immediately preceding said line to thereupon test as a final 80 line of said group.

2. In a telephone exchange system, a group of lines extending to a private branch exchange, switching apparatus for extending local and toll connections to said branch 85 exchange over said lines, and means operative upon the successive extension of toll connections to the branch exchange when all lines are initially busy in local connections 90 for progressively causing the lines to test as final lines of the group.

3. In a telephone exchange system, a group of lines extending to a private branch exchange, switching apparatus for extending local and toll connections to said branch 95 exchange over said lines, and means operative upon the successive extension of toll connections to the branch exchange when all lines are initially busy in local connections 100 for causing the lines to test as final lines of the group progressively forward from the last line toward the first line.

4. In a telephone exchange system, local and toll selector switches, a group of lines extending to a private exchange and terminating in the banks of said switches, and means operative only upon the extension of connections over said toll selector switches to a line which tests as the final line of the group for causing the line immediately preceding said line to thereupon test as the final 110 line of said group.

5. In a telephone exchange system, local and toll selector switches, a group of lines extending to a private branch exchange and terminating in the banks of said selector switches, and a relay in series with the sleeve conductor of the final line of the group operative only upon the extension of connections to said final line over said toll selector switches for changing the potential upon the sleeve conductor of the line immediately preceding said line to cause said preceding line to test as a final line of said group.

115 6. In a telephone exchange system, local and toll selector switches, a group of lines extending to a private branch exchange and terminating in the banks of said switches, a relay in series with the sleeve conductor 120

of the final line of the group operative only upon the extension of a connection to said final line over said toll selector switches for changing the potential upon the sleeve conductor of the line immediately preceding said line to cause said preceding line to test as a final line of said group, a relay in the sleeve conductor of the latter line, and means

controlled by said first relay for rendering the second relay operative. ¹⁰

In witness whereof, we hereunto subscribe our names this 18th day of September A. D., 1923.

GERALD DEAKIN.
LIPA POLINKOWSKY.
